UNITED STATES PATENT OFFICE

2,161,206

WORK HOLDER CRANKPIN GRINDER

Herbert A. Silven, Worcester, Mass., assignor to
Norton Company, Worcester, Mass., a corpora-
tion of Massachusetts

Application April 23, 1938, Serial No. 203,837

9 Claims. (Cl. 51—237)

The invention relates to grinding machines, and more particularly to a work holding, clamping and rotating mechanism for use on a grinding machine of the double head type for crank-shaft grinding.

One object of the invention is to provide a simple and thoroughly practical clamping mechanism for a work piece. Another object of the invention is to provide a mechanically operated clamping mechanism for a work piece. Another object of the invention is to provide an automatically actuated positive work clamping mechanism. A further object of the invention is to provide a spring actuated positive work clamp which is hydraulically released.

A further object of the invention is to provide a nut and screw actuated clamping jaw which is automatically actuated to clamp a work piece therein before a grinding operation and to release it therefrom after the grinding operation has been completed. Another object of the invention is to provide a work clamping mechanism including a pivotally mounted jaw which is automatically moved into an operating position when a work piece is placed in position on the work holder. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention:

Fig. 1 is an end elevation of the improved work clamping and rotating mechanism;

Fig. 2 is a vertical sectional view taken approximately on the line 2—2 of Fig. 1, showing the clamping jaw in elevation;

Fig. 3 is a vertical sectional view taken approximately on the line 3—3 of Fig. 1, on a reduced scale, showing a fragmentary section 45 through the entire work head to show the spring actuated clamping and the hydraulic releasing mechanism;

Fig. 4 is a fragmentary sectional view taken approximately on the line 4—4 of Fig. 1; and

Fig. 5 is a plan view having parts broken away more clearly to show the construction.

The invention provides an automatic clamping mechanism for a grinding machine, such as crankshaft grinding machines and the like, and which is particularly useful in a double head

grinding machine in which two opposed work supporting heads are provided with a clamping mechanism to support and to rotate synchronously the opposite ends of the work piece during the grinding operation. In the form illustrated, a 5 clamping device for holding the work during rotation may comprise a rotatable holding member and a clamping jaw which is movable into engagement with the periphery of an end of the work by a power mechanism. The clamping jaw 10 may be moved into an operative position automatically when the work piece is placed in position on the work holders and is positively rotated by means of a motor driven mechanism during the grinding operation. The particular type of 15 work drive and the arrangement of the opposed work heads have not been illustrated in detail since such an arrangement is fully disclosed in the prior Patent No. 1,837,342 dated December 22, 1931, and No. 2,113,388 dated April 5, 1938, to 20 which reference may be had for details of disclosure on the work drive mechanism. The double head crankpin grinding machine referred to in the above-mentioned patents and shown in the present drawings comprises a longitudinally 25 movable work table 20 which is adapted to slide longitudinally on a V-way and a flat way (not shown) on the base of the machine. The table 20 is adapted to support a work piece, such as a crankshaft 21, in operative relation with a rotatable grinding wheel which may be mounted on a wheel slide, such as is in common use and a well known expedient in grinding machine construction. The work table 20 is provided with a work head 25 or, if desired, a pair of opposed 35 work heads arranged on the table 20 in a manner similar to that shown in the prior United States patents above referred to. The work head or heads 25 may be formed integral with the table 20 or may be adjustably clamped thereon so 40 that the heads may be moved laterally of the table to align the axis of one head relative to the other and may also be adjusted longitudinally on the table so as to accommodate various lengths of 45 crankshafts.

The head 25 is provided with a rotatable work supporting spindle 26 journalled in bearings 27 and 28, respectively. A sprocket 29 is mounted on the spindle 26 adjacent to one end thereof and is connected by means of a link driving chain 31 50 with a sprocket 30 which is mounted on one end of a rotatable drive shaft 32. The shaft 32 is mounted in bearings (not shown) depending from the table 20. In case the improved work head is utilized in a double head machine, the work head 55

parts are duplicated on the other end of the table 20 so that two spaced opposed axially aligned work heads are provided for supporting and rotating a crankshaft for a grinding operation.

5 The shaft 32 may be rotated in any suitable manner, for example by a mechanism such as that shown in the prior U. S. patents above referred to.

In the grinding of crankpins on a crankshaft, it is desirable to support the shaft by its end 10 bearing portions which are supported in an offset relationship with the axis of rotation of the work spindles by an amount equal to the throw of the crankpins being ground so that the crankpin being ground may be swung into axial alignment 15 with the work spindle or spindles and clamped in this position for a grinding operation.

An automatic clamping mechanism is utilized 20 which rigidly locks the crankshaft 21 in place during the grinding operation. As illustrated, 20 the inner end of the work supporting spindle 26 is provided with an enlarged face plate 35 to which the pot chuck or work supporting and clamping head 36 is rigidly secured. The head 36 is provided with a fixed work supporting and locating member 37 which is provided with a partial cylindrical surface 38 to support the periphery of one end of the crankshaft to be ground. In case a double head machine is utilized, the 25 surfaces of the bearing portion adjacent to the ends of the crankshaft are each similarly supported on a partially cylindrical bearing surface 38 which is fixed to each of the work heads 36 definitely to locate the opposite ends of the crankshaft with relation to the axis of rotation of the 30 35 opposed work heads and spindles.

The work head or pot chuck 36 is provided with a pivotally mounted clamping jaw 40. The clamping jaw 40 is pivotally supported at one end on a stud 41 which is fixedly supported by the 40 work head 36. A work engaging or clamping screw 42 is screw threaded through the pivotally mounted jaw 40 and is positioned to engage the work piece, such as the end bearing of a crankshaft, at a point diametrically opposite from the 45 partially cylindrical surface 38 on the fixed work supporting member 37. A lock nut 43 is provided to lock the screw 42 in the desired adjusted position. The clamping jaw 40 (Fig. 1) is of generally circular shape which is arranged to straddle the work piece 21. The jaw 40 is provided 50 with two V-shaped notches 44 and 45 at its pivoted end which are arranged to be engaged by a spring-pressed plunger 46. The plunger 46 is supported in the work head 36. A spring 47 serves 55 normally to maintain the arrow pointed top of the plunger 46 either in engagement with the notch 44 or the notch 45 to hold the clamping jaw 40 either in an operating position, as shown in full lines in Fig. 1, or in an inoperative position, as indicated in dotted lines therein.

In order to attain one of the objects of the invention, a mechanism is provided for automatically swinging the clamping jaw into an operative position when a work piece is placed in 60 position on the work head. The inner end of the stud 41 is provided with a projecting arm 48 which carries a pin 49 at its lower end (Fig. 5). When the jaw 40 is in an inoperative position, as shown in dotted line 40a (Fig. 1), the pin 49 65 lies in the path of a flange 22 which is formed integral with the end of the crankshaft. During the movement of the crankshaft into position on the partially cylindrical supporting and locating surface 38, the flange 22 engages the pin 49 70 75 which serves to rock the stud 41 and the clamp-

ing jaw 40 from the position 40a to the full line position 40, as indicated in Fig. 1.

In order to clamp the crankshaft 21 rigidly in position on the work head 36, it is desirable to provide a clamping mechanism to secure the 5 outer end of the jaw 40 in rigid engagement with a fixed portion of the work head 36. In the preferred form, this is accomplished by a nut and screw mechanism which is automatically actuated to clamp and release the jaw 40 in timed relation with the other mechanisms of the machine. As illustrated in the drawings, a stud or screw 50 extends through an aperture 51 in the left-hand end portion of the jaw 40 (Fig. 1). The stud 50 is slidably keyed therein by means of a key 52. The upper end of the stud 50 is provided with a threaded portion 54 which is engaged by a nut 55. The lower end of the stud or screw 50 is provided with a substantially square-shaped head 56 which is provided with a substantially 20 square-shaped aperture 57 the lower surface of which is provided as an inclined plane 58 which is adapted to be engaged by means of a wedge-shaped plunger 59. A spring 60 surrounding the stud 50 and interposed between the head 56 of 25 the stud and a recessed aperture 61 within the end portion of the jaw 40 serves normally to hold the head 56 and stud 50 in a downward position.

The main bearing surfaces on the ends of a crankshaft, when the shaft is presented for the 30 grinding of the crankpins, vary somewhat in size. In order to compensate for variations in diameters of the end bearings of the shaft, the wedge-shaped plunger 59 is employed. The spring 60 pressed plunger, being wedge shaped and arranged to engage the inclined surface in the aperture 57, serves to compensate for any variations in the diameter of the bearing surface supported in the chuck. This wedge takes up the slack in the bolt so that when the nut 55 is automatically 40 rotated, the same clamping pressure will be exerted upon the shaft regardless of any slight variations in the diameter of the bearing support.

The wedge-shaped plunger 59 is mounted in 45 a horizontally extending cylindrical aperture 63 within the head 36 and is normally urged in a direction toward the right (Fig. 2) by means of a compression spring 64. The wedge-shaped plunger 59 serves as a detachable connection to 50 lock the bolt or stud 50 in an operating position during a grinding operation, as shown in Figs. 1 and 2, or to release it therefrom so as to permit the clamping jaw 40 to swing to an inoperative position for removing a finish ground shaft therefrom and replacing it with a new shaft to be ground. The plunger 59 is arranged so that it may be automatically withdrawn from engagement with the aperture 57 and the inclined surface 58 so as to release the stud or screw 50 after 60 a grinding operation has been completed. The wedge-shaped plunger 63 is provided with opposed slabbed-off surfaces 64 and 65 which are engaged by a yoke-shaped member 66 formed at the outer end of a lever 67. The lever 67 is 65 pivotally mounted on a stud 68 supported on the head 36. The lever 67 is arranged so that it may be swung automatically by a mechanism to be hereinafter described in order to withdraw the spring-pressed wedge-shaped plunger 59 after a 70 grinding operation has been completed. The spring-pressed wedge 59 serves to engage the inclined surface 58 in the aperture 57 so as to lock the lower end of the clamping stud or screw 50 rigidly to the head 28 in an operating position. 75

To obtain one of the objects of the invention, it is desirable to provide a mechanism for automatically actuating the clamping jaw, which is preferably accomplished by automatically actuating the nut 55 to clamp and release a work piece in the work head. The nut 55 is preferably provided with an integrally formed lever or arm 70 which is provided with a downwardly extending stud 71. The stud 71 rides in a groove 72 formed in a plate 73 which is fixedly mounted to a flange 74 by means of screws 74a. The flange 74 is preferably formed integral with a rod 75 which extends axially within the hollow spindle 26. A spring 76 surrounding the rod 75 and interposed between a shoulder 77 on the rod 75 and a shoulder 78 formed integral with the spindle 26 serves normally to urge the rod 75 in a direction toward the right (Fig. 2) which serves to move the plate 73 and groove 72 toward the right (Fig. 2) so as to rock the arm 70 to turn the nut 55 and thereby rigidly clamp the outer end of the jaw 40 relative to the work head 36.

A fluid pressure piston 80 is mounted on an outwardly extending portion of the rod 75 and is slidably mounted within a fluid pressure cylinder 81 which is fixed to the end of the work head 25. When fluid under pressure is admitted through a pipe 82 into a cylinder chamber 83, the piston 80 and rod 75 are moved in a direction toward the left (Fig. 3) which serves to rotate the nut 55 in the opposite direction to unclamp the outer end of the jaw 40. The lever 67 is provided with an adjustable actuating screw or stud 85 which is screw threaded through the lever and locked in adjusted position by means of a nut 86. The lower surface of the rod 75 is slabbed off, as indicated in dotted lines 88 in Fig. 2. When the rod 75 is moved toward the left (Figs. 2 and 3) to slack off the nut 55 to unclamp the jaw 40, the shaft travels a slight distance after which a shoulder 89 of a recess in the rod 75 engages the head 90 of the screw 85 and causes the screw to rock the lever 67 in a clockwise direction (Fig. 4) to move the spring-pressed wedge 59 toward the left to withdraw it from the aperture 57 and thereby release the screw 50 and the outer end of the clamping jaw 40 so that the crankshaft supported therein may be lifted from the holder. Withdrawal of the crankshaft from the holder causes the clamping jaw 40 to swing in a counterclockwise direction (Fig. 1) into the dotted position 40a so that the spring-pressed plunger 46 engages the notch 45 in the lever 40 to hold the jaw 40 in an inoperative position during the loading or indexing operation.

If desired, the piston 80 may be moved under the influence of fluid pressure in both directions to move the rod 75 and actuate the clamping nut 55 both to clamp and release a crankshaft. A port 82a is provided to admit fluid under pressure to the left-hand cylinder chamber 83a.

The operation of this improved work supporting and clamping head will be readily apparent from the foregoing disclosure. A crankpin 21 to be ground is placed in position on the partial cylindrical work supporting and locating surface 38. When the shaft is placed in this position, the flange 22 on the end of the crankshaft to be ground engages a pin 49 which serves to rock the clamping jaw 40 from the dotted line position 40a into the full line position 40 (Fig. 1). The main control lever, such as that shown in the prior United States Patent Nos. 1,837,342 and 2,113,388, is then shifted to allow fluid within the

cylinder chamber 83 to exhaust through the pipe 82, thereby releasing the compression of the spring 76, which causes the rod 75 to move toward the right (Figs. 2 and 3). The movement of the rod toward the right serves through the rock arm 67 to release the compression of the spring 64 which moves the spring-pressed wedge-shaped plunger 59 into the aperture 57 so that the wedge surface 59 engages the inclined surface 58 to lock the head 56 of the clamping bolt 10 59 in an operating position on the head 36. Continued movement of the rod 75 toward the right (Fig. 2) serves to rock the arm 70 in a clockwise direction (Fig. 5) to rotate the nut 55 also in a clockwise direction to tighten the clamping bolt 15 50 so that the jaw 40 is locked with the clamping screw 42 rigidly holding the shaft 21 in position on the partial cylindrical supporting and locating surface 38 for a grinding operation. After a grinding operation has been completed, 20 the control lever is shifted to admit fluid under pressure through the pipe 82 into the cylinder chamber 83 to cause the piston 80 and the rod 75 to move toward the left (Fig. 3) which serves first automatically to rotate the nut 55 to release 25 the clamping jaw 40 and then automatically to withdraw the spring-pressed wedge 59 so that the crankshaft 21 may be readily lifted from the machine. The lifting of the shaft from the machine serves to lift the clamping jaw 40 to an inoperative position and the spring-pressed plunger 46 holds the jaw 40 in an inoperative or open position until the next half is placed in the machine.

It will thus be seen that there has been provided by this invention apparatus in which the various objects hereinabove set forth together with many thoroughly practical advantages are successfully achieved. As many possible embodiments may be made of the above invention 35 and as many changes might be made in the embodiment above set forth, it is to be understood that all matter hereinbefore set forth or shown in the accompanying drawings is to be interpreted as illustrative and not in a limiting 40 sense. 45

I claim:

1. A pot chuck for a crankpin grinding machine having a rotatable head, a partial cylindrical bearing surface fixedly mounted on said head 50 and arranged to support and locate a work piece thereon, a pivotally mounted clamping jaw, a stud pivotally connecting one end of said jaw to said head, and automatically actuated clamping mechanism to clamp the other end of said 55 jaw to said head to secure a work piece in an operative position.

2. A pot chuck for a crankpin grinding machine having a rotatable head, a partial cylindrical bearing surface fixedly mounted on said head and arranged to support and locate a work piece thereon, a pivotally mounted clamping jaw, a stud supporting one end of said jaw, a detachable clamping device carried by the other end of said jaw automatically and detachably to clamp 60 said jaw to said head, and automatically actuated means to actuate said device to clamp the jaw in an operating position.

3. In a grinding machine having a work supporting and rotating mechanism including a rotatable spindle, a work supporting head which is fixedly mounted on said spindle, a partial cylindrical bearing surface on said head to support and locate a work piece thereon, a clamping jaw on said head which is arranged to engage 70 75

- the work piece, a nut and screw mechanism arranged to actuate said jaw, a spring actuated mechanism operatively connected to actuate said nut and screw to operate said jaw rigidly to clamp the work on said head, and a fluid pressure mechanism including a piston and cylinder operatively connected to actuate said nut and screw to move the clamping jaw to release the work.
5. A pot chuck for a crankpin grinding machine having a rotatable head, a partial cylindrical bearing surface fixedly mounted on said head and arranged to support and locate a work piece thereon, a pivotally mounted clamping jaw, a stud supporting one end of said jaw, a nut and screw carried by the other end of said jaw, a spring-pressed plunger automatically and detachably to lock said screw to said head, and spring actuated means to turn said nut to clamp the 10
jaw in an operating position.
15. 6. A pot chuck for a crankpin grinding machine having a rotatable head, a partial cylindrical bearing surface fixedly mounted on said head and arranged to support and locate a work piece thereon, a pivotally mounted clamping jaw, a stud supporting one end of said jaw, a nut and screw carried by the other end of said jaw, a spring-pressed plunger automatically and detachably to lock said screw to said head, spring 20
actuated means to turn said nut to clamp the jaw in an operating position, and means including a hydraulically operated piston and cylinder mechanism to actuate said nut in the opposite direction to release said jaw.
25. 7. A pot chuck for a crankpin grinding machine having a rotatable head, a partial cylindrical bearing surface fixedly mounted on said head and arranged to support and locate a work piece thereon, a pivotally mounted clamping jaw, a stud supporting one end of said jaw, a nut and screw carried by the other end of said jaw, a spring-pressed plunger automatically and detachably to lock said screw to said head, and automatically actuated 25
means to turn said nut to clamp the jaw in an operating position.
30. 8. A pot chuck for a crankpin grinding machine having a rotatable head, a partial cylindrical bearing surface fixedly mounted on said head and arranged to support and locate a crankshaft thereon, a pivotally mounted clamping jaw, a stud supporting one end of said jaw, a projection on said jaw which is engageable by said work piece automatically to move the jaw 30
to an operative position when a crankshaft is inserted in the chuck, a nut and screw carried by the other end of said jaw, a spring pressed plunger automatically and detachably to lock said screw to said head, and automatically actuated 35
means to turn said nut to clamp the jaw in an operating position.
35. 9. A pot chuck for a crankpin grinding machine having a rotatable head, a partial cylindrical bearing surface fixedly mounted on said head and arranged to support and locate a crankshaft thereon, a pivotally mounted clamping jaw, a stud supporting one end of said jaw, a spring pressed detent arranged to hold said jaw either in an operative or an inoperative 40
position, a projection on said jaw which is arranged to be engaged by a crankshaft when the same is inserted in said chuck automatically to move said jaw to an operative position, a nut and screw carried by the other end of said jaw, a spring pressed plunger automatically and detachably to lock said screw to said head, and automatically actuated 45
means to turn said nut to clamp the jaw in an operating position.
50. HERBERT A. SILVEN. 50

CERTIFICATE OF CORRECTION.

Patent No. 2,161,206.

June 6, 1939.

HERBERT A. SILVEN.

It is hereby certified that error appears in the printed specification of the above numbered patent requiring correction as follows: Page 3, second column, line 33, for the word "half" read shaft; and that the said Letters Patent should be read with this correction therein that the same may conform to the record of the case in the Patent Office.

Signed and sealed this 22nd day of August, A. D. 1939.

Leslie Frazer
